UNITED STATES PATENT OFFICE

LAURA RUTH, OF LANCASTER, PENNSYLVANIA

SHOE PAD

Application filed April 3, 1928. Serial No. 266,972.

The present invention relates to a small appliance to be used in connection with old types of footwear and has more particular reference to what may be designated an anti-slipping pad for use especially on the exterior of the sole of a shoe, the same being principally intended for outdoor wear.

It is well known that difficulty is sometimes experienced in walking on wet, ice, or snow covered pavements. This is particularly so where leather soled shoes are concerned. The leather, in getting wet, takes on a slimy and slippery surface, and when walking briskly on a wet surface or ice covered pavement, the wearer is liable to injury by slipping and falling.

In view of this, I have evolved and produced a simple and inexpensive article of manufacture, which can be temporarily attached to the bottom of the sole to facilitate dependable walking.

The appliance is in the form of a rubber disc equipped with an appropriate adhesive on one side to be applied against the sole of the shoe and provided on the other side with anti-slipping means.

In the drawings:

Figure 1 is a top plan view of the product as it is marketed.

Figure 2 is a transverse section taken on the line 2-2 of Figure 1.

Figure 3 is a bottom plan view showing the anti-slipping pad or appliance in place, in the sole of the shoe.

Figure 4 is a view like Figure 2, showing the covering fabric removed.

Referring first to Figure 4, it will be seen that the pad is generally designated by the numeral 5. As before intimated it comprises a rubber disc 6, the inner face of which is provided with an adhesive as indicated at 7, and the outer face of which is formed with anti-slipping means 8. This means may be in the form of ribs formed of rubber or may be a separate element. I have found it successful to employ burlap, and this has proved to be very efficient in avoiding slipping. As shown in Figure 2, the adhesive side of the disc is attached to the fabric backing and covering element 9. I might state, here,

that I propose to make this backing member substantially rectangular as shown in Figure 1, and to attach a pair of the pads thereto. The fabric can be peeled off very easily, somewhat as in the case of peeling a fabric covering off of a tire patch.

In practice, the fabric covering 9 is simply peeled off and the pads are applied to the bottom of the sole of the shoe as represented in Figure 3. The adhesive causes the pad to stick sufficiently tight for the purpose desired, but permits it to be peeled off when desired. Hence the device is merely a temporary appliance to aid in safe walking.

The simplicity of the invention is such as to permit a clear understanding to be had, after reading the description in connection with the drawing, and consequently a more lengthy description is regarded unnecessary.

Minor changes in the shape, size, and rearrangement of parts coming within the field of invention claimed may be resorted to, if desired.

I claim:

As a new article of manufacture, a safety walking appliance for attachment to the sole of a shoe, a rubber disc having adhesive material on one side and having burlap on the other side of said disc to provide an anti-slipping surface for the disc, and a readily removable covering for the adhesive surface on said other side.

In testimony whereof I affix my signature.
LAURA RUTH.
